TABLECLOTH CRUMB BRUSH

Zelda W. Rosen, Chicago, Ill.

Application October 11, 1952, Serial No. 21,804

Term of patent 7 years

(Cl. D9—2)

To all whom it may concern:

Be it known that I, Zelda W. Rosen, a citizen of the United States, residing at Chicago, in the county of Cook and State of Illinois, have invented a new, original, and ornamental Design for a Tablecloth Crumb Brush, of which the following is a specification reference being made to the accompanying drawing forming a part hereof.

In the drawing:

Fig. 1 is a plan view of a tablecloth crumb brush embodying my new design;

Fig. 2 is a front end elevational view thereof; and

Fig. 3 is an end elevational view thereof. The dominant feature of the design is shown in full lines in the drawing.

I claim:

The ornamental design for a tablecloth crumb brush, substantially as shown and described.

ZELDA W. ROSEN.
